UNITED STATES PATENT OFFICE

DAVID J. MCCLARY, OF WORCESTER, MASSACHUSETTS, ASSIGNOR TO BAKER BOX COMPANY, OF WORCESTER, MASSACHUSETTS, A CORPORATION OF MASSACHUSETTS

SHIPPING CRATE

Application filed December 5, 1932. Serial No. 645,715.

This invention relates to a crate for holding milk-bottles or other similar objects for storage, handling or shipping.

In the manufacture of such crates as heretofore carried on, crates have been made having one-piece sides and ends, and crates have also been made in which each side and end has been made up of a plurality of entirely separate narrow slats.

10 The one-piece construction was found objectionable on account of the effect of the swelling of the wide one-piece sides under the very wet conditions encountered in use. The swelling is so pronounced at the middle 15 of the sides that the edges of the sides become substantially convex and the crates rock on each other when stacked.

20 The slatted construction has been tried as a substitute for the one-piece construction but has proved slow and troublesome in assembly and also lacking in the stiffness and rigidity required to meet the severe conditions of use.

25 It is the general object of my invention to provide a shipping crate having the advantages of the slatted construction as to swelling, combined with the stiffness and ease of assembly of the one-piece construction.

30 To the attainment of this object, I provide a crate in which each side or end is composed of two or more members, which members are inter-connected in such a way that the box presents the rigidity and ease of assembly of the one-piece construction while 35 the transverse swelling at the outer edges is substantially reduced.

35 My invention further relates to arrangements and combinations of parts which will be hereinafter described and more particularly pointed out in the appended claims.

40 A preferred form of my improved shipping crate, together with a modification thereof, is shown in the drawing, in which

45 Fig. 1 is a perspective view of my improved shipping crate;

Fig. 2 is a plan view of the sides and ends assembled;

Figs. 3 and 4 are end and side views respectively of the parts shown in Fig. 2;

50 Fig. 5 is a partial perspective view of the

assembled sides and ends after an additional operation has been performed thereon, and

Fig. 6 is a view similar to Fig. 5 but showing a slightly modified construction.

Referring to Figs. 1 to 5, my improved 55 shipping crate comprises sides 10, ends 11, inner corner pieces 12, outer corner pieces 13 and the usual plurality of spacing and supporting cross rods 14.

In the process of manufacturing my improved 60 shipping crate, I first prepare one-piece wooden sides 10 and ends 11, it being understood that these sides and ends may be formed from single pieces of wood or may be built up from two or more pieces permanently 65 secured together in any usual manner as by tongues and grooves and/or gluing.

These sides and ends are then assembled by nailing them together to form a rectangular frame open at the top and bottom, as 70 shown in Figs. 2, 3 and 4. During this operation, the nails 15 are inserted in carefully spaced relation, substantially as shown in Fig. 5 and for a purpose which will herein- 75 after appear.

Reenforcing strips may be applied to the box at this stage of the construction, as indicated at 17 in Figs. 3 and 4, or these strips may be applied at the time the corner pieces are attached, as may be found most convenient. 80

After the sides 10 and ends 11 have been assembled and nailed together as above described, each assembled side or end is then separated into two parts by forming relatively wide saw cuts 20 and 21 therein. The saw cuts 20 divide each side 10 into a relatively narrow upper portion 20^a and a wider lower portion 20^b. Similarly each end 11 is divided into a relatively narrow lower portion 11^a and a relatively wider upper portion 11^b. 85

It will be noted that the saw cuts 20 and 21 are so positioned that a portion of each end member 11^a and 11^b is firmly nailed to the wider side members 20^b, and that a portion of each side member 20^a and 20^b is firmly nailed to each wider end member 11^b. Consequently the assembled sides and ends still constitute a firm and rigid and substantially unitary 100

structure after the saw cuts 20 and 21 have been formed therein, but at the same time the width of each side or end member is substantially less than in the one-piece construction. The relatively wide saw cuts 20 and 21 permit the narrowed side and end members to swell in both directions, thus reducing the swelling at the outer edges to a negligible and unobjectionable amount.

10 After the saw cuts have been formed, it will be evident that the previously assembled structure retains its original shape and that all parts remain in assembled relation, so that the corner pieces 12 and 13 and 15 cross bars 14 may be inserted or attached as easily as in the one-piece construction.

If it is desired to still further reduce the effects of swelling of the sides or ends, two saw cuts 30 (Fig. 6) may be made in each 20 side member and two cuts 31 in each end member, thus dividing each side and end member into two wider parts and one narrower part, all of which, however, have the overlapping and interconnected relation previously described, so that the parts remain in firm and rigid assembled relation after the cuts 30 and 31 have been made.

Obviously a two-part end as shown in Fig. 5 may be assembled with the three-part side 30 shown in Fig. 6, or a one-piece end as shown in Fig. 3 may be assembled with the two-piece side of Fig. 5.

In commercial use, it has been found that the single saw cuts 20 and 21 illustrated in 35 Figs. 1 and 5 are sufficient to reduce the outward swelling of the parts to a negligible amount.

From the foregoing description it will be 40 evident that my improved crate embodies the ease of assembly, together with the stiffness and rigidity, of the previously used one-piece construction, while at the same time the advantage of the slatted construction in reducing swelling of the sides and ends has been 45 attained.

Having thus described my invention and the advantages thereof, I do not wish to be limited to the details herein disclosed, otherwise than as set forth in the claims, but what 50 I claim is:—

1. A shipping crate comprising side and end members and article-supporting elements, each side and each end member comprising a plurality of pieces of wood of different widths differently arranged in the side and end members, and each wider piece in one type of member having two pieces of both of the other type of member secured to the ends thereof in spaced relation, said sides and ends thereby forming in themselves a rigid assembled structure.

2. A shipping crate comprising side and end members and article-supporting elements, each side and each end member comprising a plurality of pieces of wood of dif-

ferent widths differently arranged in the side and end members, and each wider piece in one type of member having both a wide and a narrow piece of both of the other type of member secured in spaced relation to the ends thereof, said sides and ends thereby forming in themselves a rigid assembled structure.

3. A shipping crate comprising sides, ends and article-supporting elements, each side and each end comprising two longitudinally extending pieces of wood of different widths, and said side and end pieces being arranged in different order and in spaced relation and being interconnected and secured to each other, whereby said sides and ends form in themselves a rigid assembled structure.

4. A shipping crate comprising sides, ends and article-supporting elements, each side and each end comprising two longitudinally extended pieces of wood of different widths, said pieces being reversely arranged in spaced relation in the sides and ends, and means securing both parts of each side to the wider parts of both ends, and both parts of each end to the wider parts of both sides, said sides and ends thereby forming in themselves a rigid assembled structure.

5. The method of making a shipping crate which comprises providing one-piece sides and ends, assembling and securing said sides and ends to form an open rectangular frame, and thereafter forming a relatively wide saw cut in each side and end, the cuts in the sides being substantially nearer to one edge of said rectangular frame and the cuts in the ends being substantially nearer to the other edge of said frame.

In testimony whereof I have hereunto affixed my signature.

DAVID J. McCLARY.
